UNITED STATES PATENT OFFICE

JAMES GUY EVEL, OF HAMILTON, ONTARIO, CANADA

CASKET

Application filed December 18, 1930, Serial No. 503,142, and in Canada April 10, 1930.

This invention relates to burial caskets and has special reference to a lining support for such caskets.

In the better types of burial caskets it is common to provide a cover having an opening over the head and chest of the body when in the casket, this opening being provided with a closure lid hinged at one side. Also, in such caskets it is common to hinge the portion of the front moulding adjacent the opening and also the head end moulding to the casket so that these sections of moulding can be opened out to elaborate on the effect, the casket lining being of sufficient fullness to extend out with these sections when they are opened. A portion of the casket cover lining is also left loose and of a fullness to be folded outwardly to lie over the end of the cover near the opening. The lid itself being lined, these portions of the lining folded outwardly on top of the casket as heretofore constructed to cause the raised lid to have its ends appear as though the drapery formed by the lining had been torn or otherwise removed at each end of the lid and thus detract from the appearance of the casket which it is intended should resemble a couch at the head end.

The principal object of the present invention is to provide an improved construction of lining and support therefor for the lid portion of such a casket so that the lid, when raised, may closely simulate the back of a draped or upholstered couch.

A second important object of the invention is to provide a novel construction of wing or extension for such a lid, the wings being foldable against the under side of the lid and there secured when it is desired to close the lid.

With the above and other objects in view, as will be presently understood, the invention consists in general of certain novel features of construction and combination of parts hereinafter fully described, illustrated in the accompanying drawings and specifically claimed.

In the accompanying drawings like characters of reference indicate like parts in the several views, and:

Figure 1 is a front view of such a casket, the view being slightly in perspective and the lid wings being spread.

Figure 2 is a similar view with the lid wings folded but the lid raised.

Figure 3 is a detail section through the lid and upholstery or lining and showing the supporting bracket in plan.

Figure 4 is a detail of part of the under side of the lid showing the supporting bracket in elevation.

Figure 5 is a detail view of a portion of the lid showing one wing open, the supporting bracket being dotted in position.

Figure 6 is a detail section on the line 6—6 of Figure 4.

In the embodiment of the invention herein shown there is disclosed a casket having a body 10 provided at the head end with the usual lid 11. The lining is arranged to extend over the under side of the lid as at 12 and also has sufficient width that it may be folded outwardly to drape over the front of the casket at 13 when the front moulding is hinged outwardly, to lie on top of casket at 14, and to drape back over the head end when that moulding is hinged outwardly at 15.

In the present invention a double thickness of the lining material is extended out from each end of the portion 12 to form wings 16 represented as unfolded in Figure 1 and as folded in Figure 2 and from this latter figure an idea may be obtained of the appearances of the casket as commonly constructed without wings to the lid, the unsightly gaps at the ends of the lid showing the similar gaps in the ordinary form of casket of this type.

Fixed to the lid 11 adjacent each end thereof is a bracket 18 to which is pivoted one end of a supporting rod 19 which lies between the two layers of the wing and is provided with a ball or knob at its free end which engages in the upper free corner of the respective wing. Thus the wings when expanded are supported to hang vertically below the respective rods. Fixed in spaced relation to each bracket 18 to the lid 11 is a catch 21 which, when the respective wing is folded, may have the free end of the rod 19 and its

covering of lining material engaged therebelow to hold the wing closed in the position shown in Figure 2 when it is desired to close the casket. Thus the wings may be expanded or closed at will and, when expanded cause the lid to closely resemble the back of a couch.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new is:

1. In a casket having a view opening in its cover at the head end, a lid for said opening hinged to one side thereof, a lining for said lid, and lateral wings at the ends of said lid supported from the lid to unfold on a substantially vertical axis when the lid is open and form end extensions thereof and to fold against the under side of the lid, said wings being continuations of the lid lining.
2. In a casket having a view opening in its cover at the head end, a lid for said opening hinged to one side thereof, a lining for said lid, lateral wings at the ends of said lid formed by double thicknesses of said lining, and lateral supports pivoted to the lid substantially vertically when the lid is open and extending between the thicknesses of the lining to support said wings.
3. In a casket having a view opening in its cover at the head end, a lid for said opening hinged to one side thereof, a lining for said lid, wings at the ends of said lid formed by double thicknesses of said lining, and supports pivoted to the lid and extending between the thicknesses of the lining to support said wings, each of said supports consisting of a bracket attached to the under side of the lid, a rod having one end pivoted to the bracket and extending between said thicknesses, and a ball on the free end of the rod engaging in the upper free corner of the wing.
4. In a casket having a view opening in its cover at the head end, a lid for said opening hinged to one side thereof, a lining for said lid, lateral wings at the ends of said lid formed by double thicknesses of said lining, lateral supports pivoted to the lid substantially vertically when the lid is open and extending between the thicknesses of the lining to support said wings, and means to hold said supports and wings releasably folded against the under side of said lid.
5. In a casket having a view opening in its cover at the head end, a lid for said opening hinged to one side thereof, a lining for

said lid, wings at the ends of said lid formed by double thicknesses of said lining, supports pivoted to the lid and extending between the thicknesses of the lining to support said wings, each of said supports consisting of a bracket attached to the under side of the lid, a rod having one end pivoted to the bracket and extending between said thicknesses, a ball on the free end of the rod engaging in the upper free corner of the wing, and means to hold said supports and wings releasably folded against the under side of said lid.

6. In a casket having a view opening at the head end, a lid for said opening hinged to one side thereof, and a lining for said lid having lateral extensions forming wings, said wings being adapted to fold under the lid when the latter is closed and to lie in the plane of the lid when the latter is open.

7. In a casket having a view opening at the head end, a lid for said opening hinged to one side thereof, a lining for said lid having lateral extensions forming wings, said wings being adapted to fold under the lid when the latter is closed and to lie in the plane of the lid when the latter is open, and supports hinged to the lid adjacent its ends and adapted to hold the lining in said closed and opened positions.

In testimony whereof he has affixed his signature.

JAMES GUY EVEL.
